METHOD OF PAINTING AND DECORATING

Carl J. Ernst, Milwaukee, Wis., assignor to Bro-Kade Wall Finish Co. Inc., Milwaukee, Wis., a corporation of Wisconsin

Application February 18, 1952, Serial No. 272,192

5 Claims. (Cl. 41—26)

This invention relates to a new and improved method of painting and decorating and to a pigment preparation for use therewith.

Heretofore when it was desired to superimpose a design such as a floral design on a painted wall, or the like, it was necessary in order to obtain the design either to paint each design individually or to apply a stencil and either paint or spray through the stencil with ordinary paint. Since the design usually involves several colors the stencil method necessitated putting on one color and waiting until that color was dry before applying the next color. Thus it was necessary to place the stencil over the design and remove the stencil several times before the design was completed. This process was both costly and slow, resulted in many smears due to paint running under the stencil and did not give a realistic design.

It is an object of the present invention to provide a method of painting and decorating which will permit the application of multi-colored designs on a wall, or the like, in a minimum period of time.

Another object is to provide a method of painting and decorating which will produce a more natural appearing multi-colored design on a painted surface.

Another object is to provide a method of painting and decorating which will enable multi-colored patterns to be applied economically to walls, or the like.

A further object of the invention is to provide a method of painting and decorating which will simplify the application of multi-colored designs to painted walls, or the like.

A further object is to provide a pigment cake or paste suitable for use in decorating multi-colored walls.

A still further object is to provide a pigment cake or paste which will not dry out readily.

A still further object is to provide a pigment cake or paste for use in decorating multi-colored walls which will not form a film on the wall.

A still further object is to provide a pigment cake or paste, for use in decorating multi-colored walls, which will not crumble in use.

A still further object is to provide a pigment bearing paste or cake which will impregnate a semi-dry flat paint to superimpose thereon the color of the pigment.

Still further objects will become apparent upon considering the following specification which when taken in conjunction with the accompanying drawings illustrates a preferred form of the invention.

In the drawings:

Fig. 1 is a section of a decorated wall showing a stencil in place thereon;

Fig. 2 is a partial stencil for use in conjunction with the stencil shown in Fig. 1; and

Fig. 3 is a partial stencil used in connection with the stencils shown in Figs. 1 and 2.

In practicing the present invention a plurality of pastes are prepared in various colors or shades. The pastes comprise the following ingredients in substantially the proportions given.

Color pigment, such as chrome green, chemical red, brown iron oxide, chrome yellow, cobalt blue, etc.

Parts

(C. P., dry).....	2
Aluminum stearate.....	1
Diatomaceous silica.....	1
Beeswax.....	1
Aliphatic hydrocarbons (kerosene).....	1

In the formula given above, any pigment may be used in place of those given, or percentages of those given may be mixed together to form different colors.

The beeswax referred to specifically is No. 3 commercial grade beeswax and contains 45% beeswax and 55% paraffin wax, if desired the percentage of paraffin wax may be increased, the increase being compensated for by a change in the amount of aluminum stearate used.

The aluminum stearate (powdered) is a greasy substance used in the formula to slow the drying process and to prevent skinning over of the pigment when applied to a wall.

The diatomaceous silica is merely a neutral filling agent to give the desired consistency to the resulting cake and may be replaced with any suitable filler such as other clays or silicas (e. g. gilder's whiting). The amount of filler to be added is approximately 1 part, but the exact amount is governed by the amount required to give the desired consistency.

The oil used (aphaltic hydrocarbon) may be any slow drying kerosene or that group.

The paste is formed by melting the wax and mixing the melted wax with kerosene. The color pigment and aluminum stearate are then blended into the mixture of wax and kerosene and thoroughly mixed. To this mixture is added sufficient diatomaceous silica, or other filler, to cause the mixture to solidify into a semi-hard waxy cake when cooled. The mixture is packed in containers and allowed to cool naturally.

In its simplest form the invention contemplates painting a wall, or the like, with the desired color or flat oil paint in the usual manner and allowing the paint to dry until it loses its initial tackiness and feels dry to the touch. When the paint is in this semi-dry condition a stencil is applied to the wall. The stencil may have any desired design or any desired portion of a design, such as leaves, stems, flowers, etc., cut therethrough. A dry brush is rubbed in the coloring matter described above and is then brushed across the desired apertures in the stencil to impregnate the color into the semi-dry paint on the wall surface to give it a supplemental color superimposed on the color of the painted wall. Other colors similarly may be brushed into the painted surface of the wall through apertures in the stencil to complete a multi-colored design on the wall.

The design thus induced may be varied in shades by the use of more or less paint on the brush as well as by varying the intensity of the brushing. In this manner it is possible to obtain floral designs as well as other designs which closely resemble individually hand painted work.

In order to obtain more satisfactory and more beautiful results and to do the work more rapidly it is desirable to use a paint which is adapted to be polished by the application of friction alone. Such a paint is disclosed in the U. S. Patent to Otto F. Gargen and Carl J. Ernst, No. 2,125,237, issued July 26, 1938. After this paint has dried to a point where it loses its initial tackiness and feels dry to the touch the stencil may be applied to the wall and the pattern brushed in with a dry brush, which polishes the paint exposed to the brush by the stencil. Color may then be superimposed through the stencil on the polished surface by again brushing through the stencil with a dry brush containing the appropriate colors of the paste described above. The latter brushing step impregnates the supplemental colors into the semi-dry paint surface on the wall and forms a permanent color, which, once the paint has dried thoroughly, may be washed or cleaned readily without smearing the colors.

If desired, stencil patterns may be used with relatively large areas in a supplemental color. Such larger areas may be colored with the paste described above but may be colored more readily by spraying or painting in the usual manner through the stencils with ordinary flat paints, or with the patented paint referred to above. These larger areas which have been painted with ordinary paint, which has dried to a point where it has lost its tackiness and feels dry to the touch, may have a stencil superimposed upon them with selected portions of the stencil cut out to enable the decorator to color the parts of these larger areas by brushing the colors of the paste

described above into the paint with a dry brush through the holes in the stencil.

An example of such work is shown in Figs. 1, 2 and 3 of the drawings. Fig. 1 shows a wall with one complete flower and one partially complete flower with the first stencil used in place on the wall. To decorate the wall the first stencil 10, shown in Fig. 1, is placed against the wall and the appropriate colors brushed through the holes of the stencil to bring out the leaves and the stems of the design. This design is repeated at regular intervals throughout the area of the wall by using the match marks 12 to place the stencil accurately for the next design.

After the wall has been decorated with the leafy design shown in the stencil 10, a stencil 14, having the outline of a flower is placed in position between the leaves and appropriate color is sprayed or brushed into the wall through the aperture 15, in the stencil.

After the paint in the flower has dried until it has lost its initial tackiness and feels dry to the touch, a third stencil 17, having the same outline as that of the flower and having apertures 18 therethrough, is applied over the solid color which was previously brushed or sprayed through the stencil 14 and the desired colors of colored paste described above are brushed through apertures 18 in the stencil 17 to complete the flower.

It will be understood that the hereinbefore described invention is to be taken merely as a preferred embodiment of the same, and that various modifications of the paste, as well as the means of applying the paste, may be resorted to without departing from the spirit of the invention or the scope of the subjoined claims.

That which is claimed as new and is desired to be secured by United States Letters Patent is:

1. The method of painting and decorating a surface which comprises painting the surface with a flat oil paint, allowing the paint to dry until it has lost its tackiness, applying a stencil to the wall and brushing a color pigment into the body of the paint.

2. The method of painting and decorating a surface which comprises coating the surface with a flat oil paint adapted to be polished by the application of friction thereto, allowing the paint to dry until it loses its initial tackiness, applying a stencil to the partially dry paint and brushing the exposed painted surface through the stencil to polish the paint and impose the design of the stencil on the surface, and rubbing a substantially dry pigment into the paint through selected parts of the stencil in order to form a multi-color design on the painted surface.

3. The method of painting and decorating a surface

which comprises, coating the surface with a flat oil paint adapted to be polished by the application of friction thereto, allowing the paint to dry until it loses its initial tackiness, applying a stencil to the partially dry paint and brushing through the stencil to bring out the design on the surface, and coloring parts of the design by brushing into the paint a paste comprising a color pigment embedded in beeswax through selected parts of the stencil.

4. The method of painting and decorating a surface which comprises, coating the surface with a flat oil paint adapted to be polished by the application of friction thereto, allowing the paint to dry until it loses its initial tackiness, applying a stencil to the partially dry paint and brushing through the stencil to bring out the design on the surface, and coloring parts of the design by brushing into the paint a paste comprising a color pigment embedded in a mixture comprising an oil and a wax through selected parts of the stencil.

5. The method of painting and decorating a surface which comprises, coating the surface with a flat oil paint adapted to be polished by the application of friction thereto, allowing the paint to dry until it loses its initial tackiness, applying a stencil to the partially dry paint and brushing through the stencil to bring out the design on the surface, and coloring parts of the design by brushing into the paint a paste comprising 33% color and 33% kerosene and wax mixture through selected parts of the stencil.
